UNITED STATES PATENT OFFICE

ROBERT L. CREWS, OF MADELEINE, WEST VIRGINIA

CAR STOP

Application filed October 2, 1929. Serial No. 396,888.

This invention relates to a chuck block or holder for mine cars and the like, the general object of the invention being to provide a member having a wedge part for fitting in the space between a portion of the car wheel and the rail on which the wheel rests, with means for locking the member to the rail and for attaching the member to the wheel, so that movement of the wheel toward the member is prevented.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is an elevation showing the device in use.

Figure 2 is a top plan view of the device.

Figure 3 is a bottom plan view thereof.

Figure 4 is a section on line 4—4 of Figure 2.

Figure 5 is a section on line 5—5 of Figure 4.

Figure 6 is a view looking toward the front end of the device.

In these views, A indicates a housing which is composed of the pair of side plates 1 having the inwardly extending flanges 2 on their lower edges, the pair of transverse plates 3 placed intermediate the ends of the plates 1 and having their lower edges terminating an appreciable distance above the flanges of the plates 1, these transverse plates being provided with central depending portions connected together by a bottom strip 4, to the lower face of which is connected a shoe 5 having teeth formed on its bottom, and the top plates 6 which have their inner edges spaced apart and are connected by screws or

the like to flanges 7 formed on the upper edges of the transverse plates. The side plates 1 are connected together in spaced relation by the bolts 8 which have spacers 9 thereon, and the shaft 10 which has its ends 50 threaded to receive the nuts 11. A pair of bolts 12 pass through the transverse plates and a depending plate 13 is connected with each bolt between the transverse plates by having its upper edge rolled to form an eye 55 through which the bolt passes. These eyes form spacers for the transverse plates.

A toothed jaw forming member 14 is suitably connected with the inner face of the lower end of each plate 13 and springs 15 60 have their ends connected with the plates 13 and tend to hold the plates in a position with the jaws 14 engaging the web of a rail A on which the device is placed. When the device is held on a rail by the jaws, the shoe 65 5 will engage the tread part of the rail. A cam member 16 is fastened to the inner face of each plate 13 and the shaft 10 passes through the plates and the cam members and a double cam member 17 is carried by the 70 shaft and has its cam parts engaging the cam members 16. A ratchet wheel 18 is carried by the cam member 17 and a handle 19 is attached to a hub part 20 which is rotatably arranged on the member 17. A pawl 21 is 75 slidably arranged in the hollow handle and is normally pressed into engagement with the ratchet wheel by a spring 22 in the handle. Thus by manipulating the handle, the member 17 can be given a rotary movement so as to cause its cam faces, engaging the cam members 16, to force the plates 13 outwardly 80 against the action of their springs so as to move the jaws 14 into the housing and thus permit the device to be removed from the rail. The handle may be locked with the jaws in 85 gripping position through means of the lock 23 suitably connected with the device and having its staple passing over the handle. Of course, the handle must be brought back to 90

its lowered position before it can be locked, but this can be done without moving the cam, as on the return movement, the pawl 21 will ratchet over the teeth of wheel 18.

5 The lower front corner of each plate 1 is formed with an extension 24 which is of channel shape in cross section and a block 25 of wood or the like is supported by these extensions and is fastened thereto by the 10 screws 25' and one of the bolts 8 which passes through the side plates 1. This block has a tapered front portion, the upper face of which is of arc shape, and a metal plate 26 is fastened to said face. A second plate 27 15 is formed with or connected to the lower end of the plate 26 and is fastened to the lower face of the block and has a thickened part which is toothed on its under face, as shown at 28, to form a shoe for engaging a 20 tread part of the rail.

From the foregoing it will be seen that the device can be placed on a rail with the tapered end of the block fitting in the space between a portion of the wheel and the rail, as 25 shown in Figure 1, the device being held against slippage on the rail by the toothed shoes 5 and 28 engaging the tread part of the rail and by the jaws 14 engaging the web of the rail. When the device is to be 30 removed from the rail, it is simply necessary to turn the cam member 17 by the handle 19 to force the jaws 14 away from the rail so that the device can be moved upwardly off the rail.

35 I also provide the chains 29 for fastening the device to the wheel, as shown in Figure 1, the ends of the chains being connected with one of the bolts 8 and the other ends of the chains being connected together by the member 30 which has a keyhole shaped slot therein. A portion of the chain is passed around the rim of the wheel in front of one of the spokes, as shown in Figure 1, so that movement of the wheel in the direction of the 40 arrow shown in Figure 1 will tend to force the wedge part of the device under the wheel, which will prevent further movement of the wheel.

45 It is thought from the foregoing description that the advantages and novel features of the invention will be readily apparent.

It is to be understood that changes may be made in the construction and in the combination and arrangement of the several parts, provided that such changes fall within the 50 scope of the appended claims.

What I claim is:—

55 1. A stop block for holding the wheel of a car on a rail, comprising a member having a channel in its bottom for fitting over a rail and a tapered end for fitting in the space between the rail and a portion of a wheel, spring actuated clamping jaws carried by the 60 member for clamping the web of the rail and

manually operated means for moving said jaws into inoperative position.

2. A stop block for holding the wheel of a car on a rail, comprising a member having a channel in its bottom for fitting over a rail and a tapered end for fitting in the space between the rail and a portion of a wheel, spring actuated clamping jaws carried by the member for clamping the web of the rail and manually operated means for moving said jaws into inoperative position, the top wall of the channel having toothed portions thereon for engaging the tread of the rail. 70

3. A stop block for preventing movement of a wheel of a car on a rail of a track, comprising a housing having a channel in its bottom fitting over a rail, a tapered member connected with the housing having its tapered part fitting in the space formed by a portion of the wheel and a part of the rail, toothed 80 shoes on the top wall of the channel for engaging the tread part of the rail, vertically arranged plates in the housing pivotally supported at their upper ends, jaws on the lower ends of the plates for engaging the web of a 90 rail, springs for normally holding the plates with the jaws in engaging position, cam parts connected with the plates, a cam member rotatably supported in the housing and having its cam faces engaging the cam parts and a 95 handle for rotating the cam member.

4. A stop block for preventing movement of a wheel of a car on a rail of a track, comprising a housing having a channel in its bottom fitting over a rail, a tapered member connected with the housing having its tapered part fitting in the space formed by a portion of the wheel and a part of the rail, toothed 100 shoes on the top wall of the channel for engaging the tread part of the rail, vertically arranged plates in the housing pivotally supported at their upper ends, jaws on the lower ends of the plates for engaging the web of a rail, springs for normally holding the plates with the jaws in engaging position, cam parts connected with the plates, a cam member rotatably supported in the housing and having its cam faces engaging the cam parts, a handle for rotating the cam member and means for locking the handle against 110 movement. 105

5. A stop block for preventing movement of a wheel of a car on a rail of a track, comprising a housing having a channel in its bottom for receiving part of a rail, toothed shoes connected with the bottom wall of the channel for engaging the tread of a rail, a tapered part connected with the housing for fitting in the space between a portion of the wheel and the rail, a pair of plates pivotally supported in the housing at their upper ends, jaws at the lower ends of the plates for engaging the web of a rail, spring means for holding the plates with the jaws in engaging position, cam parts on the plates, a shaft car- 120

130

ried by the housing and passing through the plates and the cam parts, a cam member on the shaft and having its cam faces engaging the cam parts, a ratchet wheel connected with the cam member, a handle movably connected with the cam member, a spring pressed pawl carried by the handle for engaging the ratchet wheel, a lock for holding the handle against movement and a chain connected with the housing and adapted to be passed around a portion of the wheel.

In testimony whereof I affix my signature.
ROBERT L. CREWS.
